LOUD SPEAKER SYSTEM

Samuel P. Zimmerman, Boston, Mass. (1 Merrill Ave., Belmont 78, Mass.); and William G. Madison, 115 Bancroft Ave., Reading, Mass.

Filed July 17, 1958, Ser. No. 749,296

7 Claims. (Cl. 181—31)

This invention relates to a loud speaker system combining the direct radiation of high and middle frequencies from a driver with corner horn back loading of the driver for low frequencies. The invention relates particularly to a loud speaker structure adapted to be positioned in the corner of a room to utilize portions of the room walls to define surfaces of the acoustic system and to specifically define portions of an exponential horn.

In brief, the invention comprises a cabinet structure having a closed resonant cavity and a driver or speaker mounted over an opening in a substantially flat wall thereof. The side walls of the cavity are so configured and constructed that they curve outwardly from the edges of the flat wall, then rearwardly and converge toward the corner of the room so that the outer surfaces thereof define a curved wall cooperating with the adjacent walls of the room to define forwardly flared exponential horn sections. The horn sections are directly coupled to the resonant cavity through a narrow slot in the rear of the cavity to the corner of the room.

It is, therefore, an object of this invention to provide a loud speaker structure providing improved low frequency response with any type of driving unit.

Another object of the invention is to provide a speaker structure exhibiting improved low frequency response and which occupies a minimum of space.

Still another object of the invention is to provide a corner horn cabinet utilizing the adjacent flat walls of a room to define sections of a horn and which horn is a truly exponential horn.

A further object of the invention is to provide a speaker system as set forth which is simple in design and economical to construct.

Additional and further objects of the invention will be apparent to those skilled in the art as the description proceeds in connection with the accompanying drawings, wherein:

FIG. 1 is a perspective view of one embodiment of the invention placed in the corner of a room;

FIG. 2 is a front elevational view of the structure shown in FIG. 1;

FIG. 3 is a horizontal transverse sectional view taken along the line 3—3 of FIG. 2; and

FIG. 4 is a sectional view similar to FIG. 3, but showing a modified form of the invention.

According to the present invention the loud speaker cabinet structure comprises a top panel or wall 2 and a bottom panel or wall 4, each being of generally square outline but with their forward corners cut off as at 6 to define a diagonal forward edge. An upstanding, substantially flat front wall 8 extends between the top and bottom walls and constitutes a support for a suitable driver or loud speaker 10 of conventional construction. The loud speaker 10 is mounted at the rear of wall 8 in a conventional manner, overlying an opening 12 in the front wall 8.

Referring now to FIG. 3, the cabinet of the present invention includes side walls 14 and 16 of curved configuration. The walls 14 and 16 are convex outwardly and extend from the side edges of the front wall 8 rearwardly and inwardly toward the corner 18 of the room. The rearmost edges 20 of the side walls 14 and 16 terminate short of the corner 18 to define a slot 22 therebetween.

The edges 20 are furthermore spaced from the walls of the room as clearly shown in FIG. 3.

The walls 14 and 16 are preferably made of a relatively thin but hard and quite stiff material, for example, a material formed by pressing ground wood into sheet form and bonding the particles with a suitable cementing material. Such sheet material is readily available under the trade name of "Masonite" and has proven eminently satisfactory for the present invention. As shown, a plurality of struts 24 extend from the bottom wall 4 to the top wall 2 and are suitably secured to each in the arrangement shown. The panels 16 are readily bent to conform to the curvature defined by the struts 24 and are fixedly secured thereto in any suitable manner, such as by gluing, screws, or both. In the form shown in FIG. 3, the side panels 14 and 16 extend forwardly past the front wall 8 to define a forward cavity 26. At least one of the walls 2 or 4, preferably the former, is provided with edges adapted to abut snugly against the walls of the room to position the cabinet in the desired relationship to the corner 18.

The cavity defined by the front wall 8, side walls 14 and 16, and top and bottom walls 2 and 4, constitutes a resonant cavity having an impedance or reflex opening (slot 22) at the rear thereof. Such resonant cavities are well known in the art and function as tuned circuits whereby only low frequency sounds exhaust from the opening or slot 22. As is clearly evident from FIG. 3, the sounds exhausting from the slot 22 are fed directly to the space between the rear edges of the side walls 14 and 16 and the adjacent walls of the room. The spaces between the rear edges of the side panels and the walls of the room constitute the throats of the horn sections, which flare forwardly and occupy the spaces between the side panels and the room walls and between the upper and lower walls 2 and 4 of the cabinet. The mouth of each horn section is at the forward edge of the upper and lower walls and extends from the ends of the edges 6 over to the side walls of the room.

Applicants have found that increased efficiency of such a system is attainable by formation of the said walls 14 and 16 in the curved manner shown. Specifically, the walls 14 and 16 follow an exponential or logarithmic curve whereby to increase the intensity of sound energy radiated from the mouth of the horn. The curvature of the walls 14 and 16 follows the formula:

$$A = A_0 (\cosh x + T \sinh x).$$

In the above formula, A is the transverse sectional area of a horn section measured in a plane perpendicular to the wall of the room. A_0 is the cross sectional area of the throat of the horn, i.e., the space between the rear edge of 20 of a side panel and the adjacent wall of the room. x is a function of the distance from the corner 18 along the room wall to the plane in which the area is being calculated. T is a parametric constant that determines the shape of the cavity and the degree of curvature of the wall panels 14 and 16. The quantity x is the distance from the corner 18 to the portion of the horn under consideration, measured in linear units, and multiplied by a factor dependent upon the resonant frequency of the resonant cavity defined by the curved walls of the cabinet and the panels 2 and 4.

Another feature of the invention resides in the fact that the area of the throat of each section of the exponential horn is equal to one-half the area of the slot 22 previously described. Thus, both portions of the exponential horn function as a single horn structure having a throat area exactly equal to the area of the impedance slot 22, which results in direct acoustic coupling of the resonant cavity to the horn. In the above formula, A_0 is always equal to one-half the area of the slot 22. It is

evident that the above formula will define an exponential curve since the hyperbolic functions can be replaced by their exponential equivalents, thus:

$$\cosh x = \frac{e^x + e^{-x}}{2} \text{ and } \sinh x = \frac{e^x - e^{-x}}{2}$$

and the equation becomes:

$$A = A_0 \left(\frac{(T+1)e^x}{2} + \frac{(1-T)e^{-x}}{2} \right)$$

where e is usually taken as the basic of the Naperian logarithms

$$e = 2.71828 \dots$$

but may, if desired, be taken as any fixed constant without effecting the shape of the curves.

The portion of the side panels 14 and 16 which extend forwardly of the front wall 8 define a forward cavity 26, which not only increases the length of the horn sections but also provides a cavity forwardly of the driver 18 which aids in radiation of low frequencies from the system. It has been found that cabinets constructed in accordance with this invention provide excellent response in the frequency range of from 20 c.p.s. to 550 c.p.s.

A cabinet constructed in accordance with FIGS. 1 through 3, wherein the parametric constant T is assigned a value of .6 and wherein the driver unit 18 is a 12-in. speaker, will have the following dimensions: The width of the cavity of the front wall 8—approximately 19 in.; the height of the cabinet between top wall 2 and bottom wall 4—24½ in.; the width of slot 22—½ in.; the space between the rear edges of the panels 14 and 16 and the adjacent walls of the room—¼ in. each; the width of each horn section at plane A (see FIG. 3), 10 in. from corner 18—1.25 in.; at plane B 15 in. from corner 18—2.55 in.; the width at plane C 20 in. from the corner—5.75 in.; and the width at plane D 24 in. from the corner—10.45 in. In a cabinet thus constructed, the side panels 14 and 16 extend approximately 3½ in. forwardly from the front wall 8. Such a cabinet proves to have excellent frequency response in the frequency range of 20 c.p.s. to 550 c.p.s.

While the drawings show a cabinet with the front thereof completely open, it is contemplated that such cabinets may be constructed with suitable decorative framing around the forward portions thereof and with the mouths of the horn sections and the front of the cavity 26 covered by suitable decorative acoustic cloth.

FIG. 4 is a horizontal sectional view through a cabinet structure constructed in accordance with the present invention, but wherein the parametric constant T of the equation set forth above is assigned a value of unity (1). In this form of the invention, the side panels 26 and 28 do not extend forwardly of the front wall 30 but terminate substantially flush therewith. A cabinet of this type may be constructed with a perfectly square bottom wall 32 and a correspondingly shaped top. A cabinet according to FIG. 4 constructed for a 6-in. speaker or driver 34 provides excellent low frequency response. In such a structure the inside height of the resonant cavity 34 would be 14 in.; the square bottom wall 32, 20 in. on each side; and the maximum width of the resonant cavity 34, 18½ in. The width of the slot 36 would still be ½ in. and the distance between the rear edges 38 of the side panels 26 and 28 and the adjacent walls of the room, ¼ in. each.

In both described forms of the invention it is to be noted that the rear portion of the resonant cavity is so related to the reflex or impedance opening that smooth entry of acoustic energy from the resonant cavity to the mouth of each horn section is provided and, as previously stated, the relation of the areas of the ports 22 and 36 to the areas of the throats of the horn sections is such as to provide optimum coupling between the resonant cavity and the horn sections with a minimum loss of energy through the entire low frequency spectrum.

While a limited number of specific examples of the invention have been shown and described herein it is to be understood that other modifications may be adopted within the scope of the invention defined by the appended claims.

Having thus described the invention, what is claimed is:

1. In a base reflex loud speaker enclosure means defining a base reflex enclosure constituting a resonant cavity having top and bottom walls, a front wall having a driver mounted therein, and horizontally curved side walls extending rearwardly from the side edges of said front wall, said side walls being outwardly convex and converging rearwardly to define a narrow slot between the rear edges thereof and comprising a reflex opening from said enclosure, said enclosure having means thereon to engage the walls adjacent a corner of a room and to hold said rear edges spaced from the walls of said room a distance substantially equal to one-half the width of said slot to thereby define a horn throat whereby said curved side walls and the adjacent walls of said room define forwardly flared horn sections coupled to said cavity through said slot and whose cross sectional areas increase as an exponential function of their lengths.
2. A device as defined in claim 1 wherein the tangent planes at the rear edge portions of said curved side walls are substantially parallel to the adjacent walls of said room.

3. A device as defined in claim 1 wherein said curved side walls each comprise a plurality of spaced rigid upstanding struts extending between said top and bottom walls and a sheet of relatively stiff and hard material secured to said struts to define said curved side walls.

4. A device as defined in claim 1 wherein said curved side walls extend forwardly past said front wall for a substantial distance to increase the length of said flared horn sections.

5. In a base reflex loud speaker enclosure means defining a base reflex enclosure constituting a resonant cavity having top and bottom walls, a front wall having a driver mounted therein, and horizontally curved side walls extending rearwardly from the side edges of said front wall, said side walls being outwardly convex and converging rearwardly to define a narrow slot between the rear edges thereof and comprising a reflex opening from said enclosure, said enclosure having means thereon to engage the walls adjacent a corner of a room to hold said rear edges spaced from the walls of said room to define a horn throat whereby said curved side walls and the adjacent walls of said room define forwardly flared horns, the curvature of each of said curved side walls being in accordance with the formula:

$$A = A_0 (\cosh x + T \sinh x)$$

- wherein A is the cross sectional area of the horn in a plane perpendicular to the room wall, x is a function of the distance from the horn throat to the plane of A , A_0 is the cross sectional area of the throat of said horn, having one-half the area of said slot and T is a parametric constant having a value of from 0 to 1.

6. A device as defined in claim 5 wherein the value of T is approximately 0.6.

7. A device as defined in claim 5 wherein the value of T is approximately 1.
